UNITED STATES PATENT OFFICE.

FREDERICK PERCIVAL SMALL, OF RIDGEFIELD, NEW JERSEY.

SHIPPING APPLIANCE.

1,385,156.

Specification of Letters Patent. Patented July 19, 1921.

Application filed November 10, 1920. Serial No. 423,120.

To all whom it may concern:

Be it known that I, FREDERICK PERCIVAL SMALL, a citizen of the United States, residing at Ridgefield, in the county of Bergen and State of New Jersey, have invented certain new and useful Improvements in Shipping Appliances, of which the following is a specification.

This invention relates to shipping appliances and has particular reference to a combined waybill accounting and receipt appliance, adapted especially for use by the express companies or other analogous carriers or transfer agents, including industrial and mercantile transactions.

Among the objects of the invention is to provide an easy and rapid means of despatching the business of a carrier such as an express company, by providing a device comprising a number of sections or coupons upon all of which the main parts of the inscription and information may be written simultaneously preparatory to the application of a portion of the device to the package to be carried therewith and thereby. More specifically one of the main objects of this improvement, distinguishing it from devices heretofore proposed, is the provision of a blank of such a nature that the shipper may fill out the blank by a simple operation of inscription, either by hand or a typewriting machine, leaving for the expressman to sign his name for the company, tear off one portion of the device for the shipper's receipt, then tear off the abstract advice and duplicate receipt to be sent or delivered to his office, and then attach the remaining portions of the device to the package preferably by the use of paste, the remaining portions including a waybill, a delivery sheet, and a waybill label.

In carrying out this invention in a form that has proved to be most highly adapted for use by a large carrier company, reference is to be had to the following detailed description when read in connection with the accompanying drawings, whereon similar reference characters are employed to indicate corresponding parts, and of which,—

Figure 1 is a plan view of a complete appliance as it may appear after being inscribed by the shipper and receipted for by the agent for the company.

Fig. 2 is a plan view of the other side of the same.

Fig. 3 is a diagram indicating the manner

of folding the device preparatory to inscribing it.

Fig. 4 is a fragmentary diagrammatic view indicating that portion of the device that is applied to the package.

Fig. 5 is a diagram indicating the operation of separating the waybill and the delivery sheet from those portions that remain affixed to the package, this separation being effected by the agent at the office of the destination preliminary to the delivery of the package and the taking of the consignee's receipt therefor on the delivery sheet.

I illustrate my improvement as an application for a prepaid transaction and shipment, but it is to be understood that it is adapted for use in connection with C. O. D. shipments or the like, with but slight modification.

As best shown in Figs. 1 and 2 the appliance comprises a single sheet of paper or the like, substantially of a rectangular form, and comprising seven main sections or coupons identified by the letters A to G inclusive, all separable from one another, either by slits or weakened lines, usually the latter. These coupons or sections are all of equal width but are not all of the same length vertically. The length of coupon A is equal to the full height or width of the sheet from which the appliance is formed. The length of coupons B and E is materially less than one half the width of the sheet. The length of coupons C, F, and G likewise is less than one half of the full width of the sheet but is greater than the length of coupons B and E. At the foot of coupons B and E are stubs B' and E' respectively, but the stub B' is notched out up to the lower edge of coupon B.

I will now describe the composition of each of the several coupons and so indicate its relationship to other parts of the appliance. In the form indicated coupon A is intended as the shipper's receipt. The upper half of this coupon indicates its nature and bears printed terms and conditions. The lower half of the coupon is ruled to provide spaces or blocks for the shipper or the agent for the shipper to inscribe information pertaining to the individual shipment, such as date, place of destination, name and address of consignee, description of the shipment, weight, charges, etc., and also places to be individually signed by the shipper and by the agent for the company. It will be

noted that all of the coupons are so printed as to bear the same identification, such as the name of the place of shipment and individual numbers so that in the event of any 5 part of the appliance becoming lost or mutilated a duplicate can be produced by reference to the identification numbers printed thereon. Coupon A is carbon spotted on its back opposite those portions upon which the 10 shipper makes his inscriptions, but a clean spot is observed at 10 where it comes adjacent to the place for the consignee's signature when folded.

Coupon B is a delivery sheet and has a 15 blank space at 11 opposite the mark X for the consignee's signature at the time of delivery of the shipment as well as a space at 12 for the signature of the delivery man. By reason of the carbon spotting at 13 on 20 the back of coupon A a carbon impression is made on coupon B coincidentally with the original inscription on the face of coupon A. Coupon C is formed at the upper right hand corner of the rectangular sheet and is slotted 25 free from coupon G at its left, but is hinged to fold downward toward the bottom of the sheet, thus overlapping nearly all of coupon D, all of coupon E, and a half of the stub E' when the appliance is ready to be inscribed. 30 The manner of folding the sheet is suggested in Fig. 3 wherein the right hand end comprising coupons C and D is first lifted and folded to the left around the line *a* and then the coupon C is lifted and folded down- 35 ward around the horizontal line *b* to the position just above described. All of the left half of the sheet is then lifted and swung to the right around the line *c* bringing coupons F and B over coupons G and C, and 40 then the coupon A is folded to the left upon coupons F and B around the line *d*. There are thus formed five plies of the sheet in the lower portion and three plies in the upper portion. The slit at *e* between coupons C 45 and G provides for the ready folding downward of the coupon C over coupon D.

Coupons A, B, C, D, and E, in folded position, are all superimposed and receive the same description that is originally written 50 upon the face of coupon A. A sheet of carbon paper inserted between coupons B and C at the time of inscription conveys the impression from coupon B to coupon C, while the carbon spot 14 on the back of coupon D 55 produces the duplication of the inscription on coupon E.

After the appliance is folded and inscribed as above described, and then signed by the shipper and the agent for the company while either still folded or subsequently thereto, the agent for the company 60 detaches coupon A along the weakened line *d* and leaves it with the shipper. The agent next detaches coupons C and D from the 65 main central portion of the sheet, along the

line *a*. Coupon C is the abstract advice and coupon D is the office copy or duplicate receipt. These coupons go to the office of the company for the usual purposes. The agent for the shipper then with the coupons F and 70 B lying flat upon the parts G and E respectively, the weakened lines *f* and *g* coinciding with each other, will lift the lower portion and swing the same upward and fold it downward flat upon the top of coupon F at 75 which time the stubs E' and B' will extend beyond the upper edge of coupons F and G, and the then under surface of stub E' will be exposed through the notch at the stub B'. See Fig. 4. Coupon G might be called an 80 anchor for the parts carried therewith, and it is provided with holes 15. The operator then applies paste to any convenient portion of the package preferably adjacent to the address of the consignee that is presumed 85 to have been applied thereto by the shipper. The operator then applies the device in the folded form just described upon the moist paste pressing the same downwardly firmly 90 first along its lower edge and smoothing it 95 out to exclude air from between the coupons and so causing the coupon G to be affixed directly to the package, coupon F to be affixed thereto through the holes 15, and the stubs B' and E' just above the upper edge of 100 coupons F and G. Thus the appliance will be carried with and by the package to its destination, the four coupons E, B, F, and G, being all retained united along the folded edge at *f* and *g*. Also the coupons E and B 105 are retained together along the line *c*. Therefore, there are free edges only along the right side and thus the appliance is carried safely by the package.

When the destination is reached and the 110 package is to be delivered, the delivery agent inserts his pencil along the bottom of the device between coupons B and F thus severing all of the coupons along the lines *f* and *g*. He then lifts coupons E and B 115 and folds them upward as in Fig. 5 and bending them downward around the lines *h* and *i* between the coupons B and E and their respective stubs B' and E', thus leaving the parts F, G, B', and E', remaining 120 fixed to the package.

As above suggested coupons B is the delivery sheet upon which is received the consignee's signature at the space 11. Coupon E is a waybill. Both of these parts carry 125 complete description and full information. The face of coupon E that is exposed in transportation is provided with a series of blank spaces 16 to receive railroad or junction stamps when being transferred from one carrier to another, and the same coupon is provided with spaces 17 for special instructions according to the nature of the shipment.

Coupon F is a waybill label and is provid- 130

ed with blank spaces at 16' for the stamping of the routes in case the waybill, coupon E, should become mutilated.

It will thus be seen that my appliance 5 comprises a rectangular sheet foldable endwise into four substantially equal panels, the first panel consisting of a shipper's receipt, while each of the remaining panels comprises two separable coupons, and the 10 whole sheet being so foldable as to comprise three plies at one end and five plies at the other end when folded, the five plies being arranged to receive inscription or descriptive matter thereon at the same time.

15 I claim:

1. The herein described shipping appliance composed of a single rectangular sheet, one end portion of which is foldable endwise directly upon the next adjacent portion and 20 a part of the portion thus folded being foldable in a different direction upon the remaining part of the end portion, the part

last mentioned being slotted free from the portion of the sheet upon which it is first folded whereby the folding in the other direction is readily possible. 25

2. The herein described shipping appliance composed of a substantially rectangular sheet foldable endwise into four substantially equal panels bearing appropriate 30 imprints constituting the first panel, a shipper's receipt, the second panel a way bill label and a delivery sheet, the third panel an anchoring means for securing the device to a package and a waybill, and the fourth 35 panel an abstract advice and a duplicate receipt, the sheet being so formed as to be readily folded with three plies at one end and five plies at the other end whereby an inscription written upon the first ply may 40 be impressed at the same time on each of the four plies beneath it.

FREDERICK PERCIVAL SMALL.
